GAS LAMP CONSTRUCTION

Joseph O. Cadieux, Meriden, Conn., assignor to
Connecticut Telephone & Electric Corpora-
tion, Meriden, Conn., a Corporation of Dela-
ware

Application March 14, 1930. Serial No. 435,731

6 Claims. (Cl. 173—328)

My invention relates to lamps employing a luminescent gas, such as neon, within transparent or translucent tubes and more particularly to that type used for display purposes.

5 Heretofore, lamps of this character have been more or less permanently located. This being due to the fact that a very high voltage frequently varying sometimes from 2000 to 20,000 volts or more is required for their operation and 10 that the transformer used to step-up this voltage is usually located in a more or less remote place from the lamps, the same being connected to the usual standard electric lighting systems operating at 110 or 220 volts. It can be readily 15 understood that great danger and expense is involved in wiring systems of this type.

Furthermore, in changing the various display indicia depicted by lamps of this character heretofore used, it was necessary to change many 20 parts of the supporting structure in conformity with the new indicia desired, and oftentimes move the entire assembly to a new location, all of which necessitated expensive rewiring and installation.

25 One of the principal objects of my invention provides a structure having a lamp that is readily interchangeable without the resultant danger usually coincident therewith by having the contact elements isolated.

30 Another object provides a structure that is portable and capable of being connected to any near-by source of current of low voltage, a step-up transformer being located within the structure for this purpose.

35 A further object provides a lamp structure that is easily disassembled for repairing or replacement of parts, the various parts being so correlated as to form units.

A still further object provides means for the 40 segregation of the high tension side of the transformer by inclosing the same within a housing or inner casing, located in a cabinet or base.

Other objects and advantages will be apparent 45 from the following description, appended claims and annexed drawing.

Referring to the drawing wherein:

Fig. 1 is a vertical sectional view of my device, the lamp being shown in front elevation.

Fig. 2 is a fragmentary end elevation, the 50 lamp unit being shown in end elevation with the associated parts in section.

A cabinet base or casing 4 has mounted thereon a tube socket or base 5 adapted to receive and support a lamp tube 6. Within the cabinet 55 is mounted a cup 8 formed preferably of insulat-

ing material and supported by a flange 9 within the base in a manner hereinafter described.

Inside of this cup is mounted a transformer 10 of suitable construction which may be supported by brackets 11 connected to the cup in a suitable manner as for instance by means of screws 12. The current to the low tension side of the transformer is supplied thereto by wires or conductors 13, which are connected to a source of current supply for instance through the medium of a socket plug 14 secured in the base section.

A switch 15 may be associated therewith and may be of any desired type. The cup 8 is provided with an upper part 16, constituting 70 a tube socket which is also formed preferably of insulating material and has a flange 17 which is secured to the flange 9. This cup and socket are secured to the under side of the cabinet by screws 18. Spring contact clips 75 or terminals 19 are secured in recesses 20 in the member 16 by means of tubular eyelets 21 which also serve to receive the high tension output leads 22 of the transformer. An insulating cover, cap or shield 23, for instance, 80 of formica is secured to the upper part 16 of the cup, for instance, by being frictionally engaged within a flange 24 formed thereon, and is flush with the upper surface of the base 4 and serves to support the lamp base 5. This 85 shield has two openings 25 for the prongs 26 of the lamp base.

The chambers or recesses 20 afford suitable 90 space for isolation of the terminal clips 19 and yet access to these chambers 20 is prevented by the cap or cover 23 except through the small openings 25 provided, which are just large enough for the terminal prongs 26 of the lamp 5. It will be understood that the prongs or 95 clips may be suitably shaped for interconnection and preferably by tongue and groove portions so as to snugly hold the parts together and prevent separation. Of course these terminals must have excellent electrical conducting 100 characteristics so as to avoid heating under the high tension to which they are subjected.

The lamp base 5 is preferably formed of insulating material and has two grooves or chambers 27—27 and an intermediate wall 28. 105

Bus bars 29 are secured in the grooves 27 for instance by inserts 30. The terminal prongs 26 project through the base section and form contact with the bus bars 29 for instance by being riveted thereto.

Spring contact clips 31 are secured to the outer ends of each of the bus bars 29 by means of rivets 32 and serve to receive, hold and form electrical connection with the lamp tube 6.

- 5 Covers 33 preferably of insulating material having openings 34 at opposite ends thereof for the tube ends serve to inclose the interior for protection against the high tension current and may be secured in any suitable manner.
- 10 The lamp 6 may be of any suitable character comprising some form of tube having suitable electrodes 35 with terminals 36 for engagement with the contact clips 31. This tube will contain a suitable form of gas, such as neon under proper operating conditions.

15 A reflector plate or shield 37 has its lower end embedded in the base 5 and is positioned in proximity to the lamp tube and serves also to protect the same.

- 20 It is understood that various forms of the lamp indicative of wide variety of colors, words, phrases, numbers, symbols and other indicia may be formed thereby and that the tube may be readily changed in respect to the base. Other 25 bases may be employed of various lengths and widths to accommodate different sizes of the lamps, without the necessity of using more than one cabinet. The cabinet having within it the 30 transformers permits the device to be placed in any convenient place without the necessary external high tension wiring usually required.

35 The same socket base can be used for tubes or words of different lengths by simply locating the contact clip 31 at the proper points on the bus bars 29 to correspond with the spacing of the ends of the tube.

40 Automatic turning on and off of the current in the low tension side of the transformer may be effected by means of a suitable flasher (not shown).

45 It will be seen from the foregoing that I have provided such a novel and new arrangements of parts that this device may be made, sold and purchased in units, thereby eliminating the necessity of having an entire assembly for each form of lamps used.

50 It is further understood that various changes and modifications may be made in the construction of my device without departing from the spirit of the invention and scope of the appended claims.

I claim:

1. A connector for a gas lamp comprising a

55

base having grooves, bus bars secured therein, terminal prongs secured to the inner ends of said bars and projecting from said base, contact sockets secured to said bars within said grooves, and insulating plates covering the bus bars in said grooves and having passages to permit the terminals of a gas tube to be inserted into said sockets.

2. A gas lamp connector comprising a base having two projecting terminal prongs near the center of the base, two bus bars having inner and outer ends in the base and having their inner ends secured to the inner ends of the prongs and a gas tube having its ends connected to the outer ends of the bus bars.

3. A gas lamp connector comprising a base having grooves in one face, bus bars anchored in said groove, a terminal prong riveted to one end of each bus bar and a socket riveted to the opposite end of each bus bar, to receive one end of a gas tube.

4. In a gas lamp connector, a socket for the lamp comprising an elongated base portion, front and rear wall portions defining aligned elongated chambers, a bus-bar in each chamber, a 100 terminal prong carried by the inner end of each bar and projecting through said base portion, a spring terminal clip fastened to each of said bars in said chambers and a perforated cover for said chambers having perforations to permit insertion of the ends of a gas tube into said clips, all of said parts forming a unitary structure.

5. A gas lamp connector comprising an elongated, insulating base, bus-bars mounted in said base longitudinally thereof and in alignment 110 with each other, a terminal prong secured to the inner end of each bus-bar and projecting outwardly through the base, a tube receiving socket secured to the opposite ends of each bus-bar, and an insulating cover for said bus bars having an opening in line with each of said sockets and on the side opposite to said prongs.

6. A glow lamp base comprising an elongated insulating body, having separated elongated grooves in its front, two bus bars housed in said grooves in the body and extending respectively from points near the center to points near the outer ends, contact prongs riveted to the inner ends of the respective bus bars and projecting from the rear of the body, and tube-holding 125 clips secured to the outer ends of the respective bars and housed in the body.
